DISPLAY RACK

Arthur Goldstein, 11 Winchcombe Way, Scarsdale, N.Y.
10308, and Theodore Sobel, 66 Glenview Road, South
Orange, N.J. 07079

Filed June 10, 1968, Ser. No. 12,279

Term of patent 7 years

Int. Cl. D6—01

U.S. Cl. D80—10

FIG. 4

FIG. 5

FIG. 1 is a right side elevational view of a display rack embodying our new design;

FIG. 2 is a top plan view thereof looking in the direction of the arrows 2—2 in FIG. 1;

FIG. 3 is a front elevational view thereof looking in the direction of the arrows 3—3 in FIG. 1;

FIG. 4 is a rear elevational view thereof looking in the direction of the arrows 4—4 in FIG. 1; and

FIG. 5 is a bottom plan view thereof looking in the direction of the arrows 5—5 in FIG. 1.

We claim:

The ornamental design for a display rack, as shown.
